TUBULAR COIL YARN PROCESSOR

Paul M. Cole, Claymont, Del., assignor to E. I. du Pont de Nemours & Company, Wilmington, Del., a corporation of Delaware

Application November 9, 1949, Serial No. 126,288

7 Claims. (Cl. 68—181)

This invention relates to an apparatus for fluid treatment of textile fibers in the form of continuous filaments, threads, yarns, and like structures. More particularly, the invention is concerned with an apparatus for the treatment of a traveling filamentous structure by parallel flow of treating fluid and suitable for washing, desulfuring and bleaching treatments in a continuous process for preparing rayon from viscose.

Viscose rayons are commonly processed in the form of bobbin or bucket cakes which inherently develop uneven tensions throughout the package with the result that the yarns are non-uniform in denier, tenacity, elongation, dyeability, fatigue resistance, etc. Although yarns have been processed in a continuous manner on advancing reels, the tension that must be maintained on the yarns for even and effective advancement prevents relaxation of the yarn. Furthermore, such advancing reels are expensive to manufacture and maintain.

An alternative method for continuous treatment has been proposed in which thread is treated with fluid while passing through a long tube. In order to make this practical, the tube must be bent into some sort of coil to make the apparatus compact. Attempts have been made to use smooth-walled tubing in the shape of a simple helix, the shape obtained by winding the tubing around a cylinder, the tubing being provided with an ejector at the exit end to suck liquid and thread through the tube. With this arrangement it has been found impossible to make thread pass through the tube. The thread hugs the wall of the tube and builds up so much frictional drag that the thread piles up in the tube within the first few turns of the helix. Pulling on the thread at the exit end of the tube only makes matters worse; the thread hugs the tube wall even more tightly. Even if it were possible to pull the thread through the tube, this would be disadvantageous because it is usually desirable to treat the thread while it is either in a relaxed condition or under a predetermined controlled amount of tension at all points.

It is an object of the present invention to provide an improved practical apparatus employing a long, coiled passage for treating filaments, threads, yarns, and other filamentous structures with fluid in a continuous manner. Another object of the invention is to provide such an apparatus which is suitable for continuously treating filamentous structures with different fluids. A still further object of the invention is to provide such an apparatus which is readily strung-up with yarn in starting, and which automatically transfers the yarn from one treating coil to the next with a substantially complete change of treating fluid. Other objects will become apparent from the following description and the appended claims.

The apparatus of this invention comprises a long, coiled passage provided with injector means adapted to continuously introduce yarn or other filamentous structure and treating fluid into one end of the passage and project the fluid through the passage at high velocity, and transfer means for separating the treating fluid from the yarn and transferring the yarn to the next operation. An

2

especially useful form of the apparatus comprises a series of such coils for successively treating the yarn with different fluids, and including transfer means adapted to transfer the yarn automatically from one coil to the next in the series. Preferably, for yarn bundles of normal size, i. e., not over 2000 denier, the passage has a non-uniform shape provided by forming a tube into a coil having reverse curvatures, by making the passage wall uneven, or by forming a twisting passage into a coil, or by 10 a combination of these. An especially desirable coil is a compound helix formed by coiling a tube modified to have a non-circular cross-section, e. g., oval, and twisted lengthwise.

The apparatus is so designed that treating fluid will 15 completely surround the yarn during most of its travel and minimize direct contact of the yarn with the passage wall. This is accomplished by the manner in which the treating fluid is projected through the passage and by the nature of the passage. The injector means is designed to provide for forcing the treating fluid through the passage at a high velocity, well above the critical velocity for streamline flow, so that turbulent forces will be produced which will eliminate binding of the yarn in the passage. It has been found that the fluid will be effective in attaining this purpose if the shape of the passage is such 20 that a taut yarn will contact the passage wall continuously for only a short distance at any place before being drawn out of contact. This is accomplished by making the coiled passage of non-uniform shape in one or more ways which 25 include making the passage wall uneven and utilizing reverse curvatures in making the coil. Preferably a helical, undulating or twisting passage is coiled to provide a passage having compound curvatures, e. g., a compound helix. These all reduce binding of the yarn in the passage, 30 as compared with a uniform helical tubular passage, apparently by increasing the turbulence of the fluid and by enabling it to get between the yarn and the passage wall to completely surround the yarn during most of its travel.

40 In the drawings, which illustrate embodiments of the invention,

Fig. 1 is a front elevation of one form of apparatus for the treatment of a traveling yarn with four liquids,

Fig. 2 is an enlarged sectional elevation of an injector 45 for introducing yarn and treating liquid into a coiled tube or into the first of a series of coils,

Fig. 3 is an enlarged sectional elevation of transfer means for connecting one coil to another, which combines 50 means for separating the yarn and treating liquid emerging from the first of the two coils with means for introducing the yarn and another treating liquid into the second coil,

Fig. 3A is a cross-section on line A—A of Fig. 3, with tube 42 and screen 45 removed for clarity,

Figs. 4 to 7 are plan views of different tube coils which 55 may be employed in the practice of the invention,

Fig. 8 is a perspective view of a preferred form of tube,

Fig. 9 is a plan view of a coil formed from the tube shown in Fig 8, and

Fig. 10 is a plan view of a coil formed from a tube 60 provided with an irregular surface to enable fluid to pass between the tube surface and the yarn to prevent binding. The tube is shown partially in section.

Referring to Fig. 1, a yarn 10 is drawn from a cake or spool 11, which is mounted on a suitable support 12. 65 The yarn passes through a guide 13, over an idler 14, and around a pulley 16 of small diameter mounted on the shaft of variable speed electric motor 17. The idler and pulley are of cylindrical shape and the yarn is given multiple turns around the two to prevent slipping. The idler 70 is larger in diameter and set at a slight angle to the pulley to space the turns so that the yarn will run free. The yarn then passes into injector 20, which is shown in detail in

Fig. 2 and will be described subsequently. Treating liquid is supplied to the injector jet through pipe 21 at sufficient pressure to provide the required velocity of flow, 50 to 300 pounds per square inch being the usual range. Additional treating liquid is supplied through pipe 22 at low pressure and passes through the injector with the yarn.

The treating fluid and yarn pass into coiled tube 40. While the side of the coil shown in the figure appears to be that of a simple helix, a top view of the coil would show it to be a flattened or pinched-in oval as shown in Figs. 4 and 5. It may also have other compound shapes, as will be discussed subsequently in connection with Figs. 4 to 7. The tube can vary widely in length and internal diameter but for maximum efficiency with yarn bundles of normal size, i. e., not more than 2000 denier, tubes of about $\frac{1}{4}$ inch inside diameter are preferable and good results are obtained with tubes of about $\frac{3}{16}$ inch to $\frac{1}{2}$ inch. It is not ordinarily desirable to use larger tubes than necessary to accommodate the yarn without binding because of the increased through-put of liquid necessary to maintain a high velocity of flow. With larger bundles of yarn, such as ropes or tows of up to 200,000 denier, the tube diameter may be increased to as much as 3 inches to accommodate the bundle. The tube may be from 5 to 200 or more feet in length, depending upon the length of treatment desired. For the sake of compactness the tube should be coiled so as to have a radius of curvature of about 3 to 6 inches at the bends. Thus a 50 foot length of tubing may be formed into a coil having from 5 to 30 complete loops.

The exit end of tube 40 extends into a connector device 41 which separates the treating liquid from the yarn and automatically transfers the yarn into a second coiled tube 63. This device is shown in detail in Fig. 3 and will be described subsequently. Separated treating liquid emerges from the device through pipe 42 and may be recirculated to the injector 20. A second treating liquid is supplied to the connector device at high pressure through pipe 43, and additional treating liquid may be supplied at low pressure through pipe 44. The yarn and treating liquid pass through tube 63, which is coiled in a similar manner to tube 40. Tube 63 is connected with a third coiled tube 65 by a device 64 which is identical in all respects with connector device 41. Coiled tube 65 connects in turn with a fourth coiled tube 67 through a connecting device 66, which is again identical with device 41.

This last tube 67 discharges into a tank 70 through a larger bent tube 71 which serves to reduce the velocity of the liquid flowing out of the tube. Tank 70 is provided with an overflow pipe 72 through which the liquid may pass to the sewer or be recirculated to coil 67. The transfer device following this last coiled tube 67 comprises a guide wheel 73 in tank 70 and a second guide wheel 74 outside of the tank to direct the yarn to the next operation, here shown as a wind-up machine 80. If automatic transfer were desired the tank 70, bent tube 71, overflow pipe 72 and guide wheel 73 would be replaced by a device embodying the construction of the separating and transfer features of the connector device 41, the injector portion of the latter being omitted.

The wind-up machine 80 is of conventional construction and, since it forms no part of the present invention, will not be described. The yarn could also pass to other operations before being collected, such as a dryer or a staple cutter. It is also obvious that the yarn to be treated need not come from the cake or spool 11 shown; the yarn could come directly from the spinning operation without intermediate winding.

The coils are shown supported by platforms 99 attached to a column 91. The particular arrangement shown is merely a convenient one; the coils could be all supported at the same level in any convenient manner. The number of coils used depends, of course, on the operations to be performed. The four coils shown are suitable for performing the operations of desulfurizing, bleaching,

and washing. For desulfurizing, a dilute alkaline solution of sodium sulfide would be introduced into coiled tube 40 by means of injector 20. Water would be introduced into tube 63 by means of device 41 to wash the yarn. A solution of sodium hypochlorite would be introduced into tube 65 to bleach the yarn. Finally, the yarn would be washed again in the last coiled tube 67.

Injector 20 is shown in detail in Fig. 2. It comprises a reservoir chamber 23 from the lower part of which a funnel-shaped opening 24 connects with a small tube 25 extending about $\frac{1}{8}$ to $\frac{1}{4}$ inch inside of a larger tube 26 and forming therewith an annular orifice through which high pressure liquid is forced to provide the injector action. Tube 25 need only be large enough to accommodate the yarn to be treated. Tube 26 must be enough larger to provide the required size of annular orifice for the desired rate of flow. Tube 26 is screwed into a cylindrical hole in block 27 so that the block forms an annular chamber at the end of the tube which communicates with the annular orifice. The other end of tube 26 is connected with tube 40. The small tube 25 is held in proper position by a block 28 fitting into the hole in larger block 27. Block 28 is hollowed to provide the funnel-shaped opening 24, previously mentioned, into the small end of which the tube 25 is secured, as by brazing. Pipe 21 is screwed into the block 27 and communicates with the annular chamber at the end of tube 26 to supply high pressure liquid.

Reservoir chamber 23 is formed by securing a section 30 of large tube 29, about 2 to 3 inches in both length and diameter, between end pieces 30 and 31 by means of bolts 32 passing through holes in end piece 31 and screwing into threaded holes in end piece 30. Block 27 is secured to the opposite face of end piece 30 by an annular ring 33 which engages projections on block 27, the ring being held by bolts 34 screwing into end piece 30. A conical opening through end piece 30 connects the funnel-shaped opening 24 in block 28 with the lower part of chamber 23. End piece 31 is provided with an opening 35 into the upper part of chamber 23, through which the yarn passes into the chamber. Pipe 22 is screwed into a threaded opening in end piece 31, which communicates with the lower part of chamber 23.

In operation treating liquid is supplied through pipe 45 22 at a rate which will maintain a pool in the chamber above the level of the funnel-shaped opening 24. Yarn enters the chamber through opening 35 and is carried out of the chamber through opening 24 with liquid from the pool. Treating liquid supplied under pressure through 50 pipe 21 travels at high velocity through the annular orifice formed between tubes 25 and 26. This creates a low pressure at the end of tube 25 which sucks the yarn and treating liquid from the chamber 23 through tube 25 and into tube 26. A part of the kinetic energy of the 55 high velocity stream emerging from the annular orifice is reconverted to pressure in tube 26 and at the end of tube 40, and serves to drive the liquid through coiled tube 40 at the necessary velocity to prevent the yarn from binding in the coil. The liquid and yarn then emerge from the 60 opposite end of tube 40 into connector device 41.

Connector device 41 is shown in detail in Fig. 3. In principle this device is the injector 20 of Fig. 2 with the addition of means for continuously introducing the yarn into the reservoir chamber in a high velocity fluid stream, separating the yarn from the fluid stream and then conducting the fluid out of the chamber and away. This comprises the addition of an inlet tube 40 to carry the yarn and fluid stream into the upper part of the chamber and a separator tube 42 to catch the fluid stream as 70 it leaves the inlet tube 40 and conduct the fluid away from the chamber, the end of the separator tube being covered with a screen 45 set on an angle to deflect the yarn out of the fluid stream and toward the injector opening during automatic string-up. The device 41 is illustrated as a connector between coiled tube 40 and the

next coiled tube 63, the exit end of tube 40 being, in this case, the inlet tube mentioned above.

As in the case of injector 20, a small tube 46, having an inside diameter sufficient to accommodate the yarn without binding, extends a short distance inside of a larger tube 47 to form therewith an annular orifice through which liquid supplied by pipe 43 is forced at high velocity. Tube 47 is screwed into block 48 and tube 46 is brazed into the small end of a funnel-shaped opening in block 49, which is in turn supported in a cavity in the opposite end of block 48 from the tube 47. Tube 47 is connected to the next coiled tube 63 of the series. The funnel-shaped opening in block 49 opens into a chamber 50 formed by a section of large tube 51 held between end pieces 52 and 53 by bolts 54. An opening in end piece 53 accommodates the inlet tube 40. An opening directly opposite in end piece 52 accommodates the end of tube 42, which is approximately twice the diameter of

cent of the total water discharged from tube 40 for the various conditions shown. In cases of 100% discharge into tube 42, the amount of water deflected by screen 45 into chamber 40 was of the order of 3 or 4 drops out of 20 pounds of water passing through the screen into tube 42, and was too small to consider. In the table, tube angle refers to the angle of the axis of tube 40 with the axis of tube 42, and screen angle refers to the angle of the screen with the axis of tube 42. The tests show that a high efficiency of separation of yarn from liquid is possible with a considerable variation in conditions. The most satisfactory results were obtained with a screen of 0.011 inch wire and 18 x 14 mesh mounted at a 40° angle, when treating yarn ranging in size from 550 denier to 1650 denier. The separator will function in any position, but the horizontal position described is preferred for the present purpose because of its better adaptability to space requirements.

TABLE I

Test	Tube Diameter in Inches		Tube Angle, Degrees	Water Velocity, Ft./Min.	Screen Angle, Degrees	Screen Material	Wire Size, Inch	Mesh	Percent Opening	Percent Discharge into Tube 42
	Tube 42	Tube 40

H	1	3/8	0	380	59	Brass	.011	18 x 14	67.9	100.0

tube 40 and is located in approximate axial alignment so as to catch the stream of liquid emerging from tube 40. Tube 42 is held in place by a plate 55 which presses a packing ring 56 into a groove in tube 42 and against end piece 52. Plate 55 is drawn against end piece 52 by bolts 57 screwing into the latter. Plate 55 also engages projections on block 48 to hold the injector assembly against end piece 52 below tube 42. The opening through end piece 52 which connects with the funnel-shaped opening in block 49 is at the lower part of chamber 50 directly below the end of tube 42. The end of the tube is cut at a 40° angle toward this opening and is covered with a screen 45, ordinary screen wire of the type used in windows being suitable. With this arrangement liquid emerging from tube 40 passes through the screen into the larger tube 42 and is carried away. Yarn, traveling with the liquid through tube 40, cannot get through the screen and is deflected downward toward the opening into the injector during automatic string-up. Liquid to be used in treating the yarn during passage through the next coiled tube 63 is supplied to chamber 50 through pipe 44. This pipe is connected to the end of a passageway 58 in end piece 52 by nipple 59, which is screwed into the passageway, and union 60, which joins the nipple and pipe. Although the whole of passageway 58 is not visible in this view, it communicates with chamber 50 at a point below screen 45 as shown in Fig. 3A.

Liquid is supplied through pipe 44 at a rate which will maintain a pool in chamber 50. The level of the pool should be below the lowest point of the screen. Treating liquid supplied at high pressure through pipe 43 passes through the annular orifice formed by tubes 46 and 47 at high velocity, which causes yarn and liquid to be sucked out of chamber 50 through tube 46 and be carried through tube 47 into coiled tube 63. The high velocity stream entering through the annular orifice and the stream entering through tube 46 exchange momentum, and part of the kinetic energy of the high velocity stream is reconverted to pressure head which drives the liquid through the coiled tube 63.

The effectiveness of the separator in carrying off water discharged from tube 40 is shown in Table I. The weight of water discharged into tube 42 was determined as a per

cent of the total water discharged from tube 40 for the various conditions shown. In cases of 100% discharge into tube 42, the amount of water deflected by screen 45 into chamber 40 was of the order of 3 or 4 drops out of 20 pounds of water passing through the screen into tube 42, and was too small to consider. In the table, tube angle refers to the angle of the axis of tube 40 with the axis of tube 42, and screen angle refers to the angle of the screen with the axis of tube 42. The tests show that a high efficiency of separation of yarn from liquid is possible with a considerable variation in conditions. The most satisfactory results were obtained with a screen of 0.011 inch wire and 18 x 14 mesh mounted at a 40° angle, when treating yarn ranging in size from 550 denier to 1650 denier. The separator will function in any position, but the horizontal position described is preferred for the present purpose because of its better adaptability to space requirements.

A certain amount of treating liquid will be carried by the yarn to the next treatment. This can be minimized by providing for the outlet lips of coiled tubes 40, 63 and 65 to wipe the yarn as it leaves tube 40. The discharge end of the tube is slotted on the underside and the slot is fitted with resilient lips 61 (Fig. 3A). During string-up the yarn discharges against the screen. After the yarn is picked up and the slack eliminated, the yarn is pulled into the slot. The resilient lips 61 of the slot then wipe the yarn as it leaves the tube to go to the next coil as shown in Fig. 3A.

The shape to which the treating tubes are coiled is important to the successful operation of the apparatus. Suitable shapes are shown in Figs. 4 to 7. The one shown in Fig. 4 may be described as a straight-sided oval or, more exactly, as an oblong with semicircular ends and parallel straight sides. A more effective shape is provided by bending the sides of the oval inwardly to provide reverse curvatures, as shown in Fig. 5. Another method for providing reverse curvatures is to bend the tube into the shape of the figure 8, as shown in Fig. 6. The reverse curvatures prevent the yarn passing therethrough from continually contacting the wall of the tube, increases the turbulence of the fluid and enables the fluid to surround the yarn and prevent it from binding on the tube wall during its travel.

The fluid can be caused to swirl around the yarn, which is even more effective in preventing the yarn from binding against the wall, by bending the tube into a long, open helix of small diameter having, for example, a pitch of 2 to 10 inches, which helix is then wound into a coil of larger diameter, as shown in Fig. 7. This shape can be achieved by twisting the tube around a taut straight wire and then forming the combination into a coil. Two coils can be made simultaneously by twisting two lengths of tubing about each other and then forming both together into a coil shape. The shape of the coil formed from the small diameter helix may be the compound helix shown in Fig. 7, or it may be one of the shapes shown in Figs. 4 to 6.

A preferred method of making the fluid swirl around the yarn is by twisting a tube having a non-circular cross-section lengthwise about its axis, to provide a spiral sug-

gestive of the rifling of a gun, and then coiling the tube. A non-circular cross-section can be provided by indenting one or more creases down the length of a metal tube, or by partially flattening the tube to an oval shape. A suitable tube would have an oval cross-section, approximating 0.200 x 0.284 inch, and be twisted approximately three turns per foot, as shown in Fig. 8. The twisted tube may be coiled to any of the forms described, such as a helix 6 to 12 inches in diameter as illustrated in Fig. 9. Not only is this type of coil highly effective for processing 10 yarn, but the formation of a compound helix by merely flattening, twisting, and then coiling metal tubing is the most practical fabrication technique discovered.

The tubing used for the coil should not be too smooth. Ordinary glass and plastic tubing are less desirable than other materials for this reason. Metal or plastic tubing can be improved by pressing irregularities into the outside surface to form irregularities in the inner surface. The tubing may also be made uneven by corrugating or sand-blasting. Elastomeric tubing made with an irregular or bumpy internal surface is among the best. A desirable type of tube can be produced by mixing particles of vulcanized rubber into a batch of unvulcanized rubber to be used in making the tube, or by mixing high and low molecular weight polymeric material, which will produce distortion as the tube is extruded. The tube can also be distorted or made uneven by applying an irregular outer cover prior to vulcanization, or by an irregular curing mold. In some cases a wrinkled surface can be produced by swelling the surface of the rubber with a solvent, such as benzene, before the rubber is vulcanized. Other methods for producing suitable irregular wall surfaces will readily occur to one skilled in the art. Such wall surfaces of the type illustrated in Fig. 10 offer reduced resistance to movement of yarns, apparently because they enable the fluid to get between the yarn and the wall to prevent binding.

The apparatus disclosed will operate effectively only when the velocity of the treating fluid is sufficient to provide forces which will keep the yarn from binding in the passages. The velocity of liquid flow should be well above the critical velocity for streamline flow. For re-

5
10
15
20
25

diameters of tubes 25 and 26 (Fig. 2), supplying liquid at the proper pressure through pipe 21, and controlling the speed of motor pulley 16 (Fig. 1) to pass the yarn through the tube at a speed which is in proper relation to the liquid velocity, tension on the yarn during its travel through coiled tube 40 can be completely eliminated or held to some desired low tension value.

For a given yarn velocity the performance of most coil forms tends to improve as the liquid velocity is increased up to an optimum of approximately 85% of the input yarn velocity, and then drops off between 85% and 100% of yarn velocity. The optimum depends upon the coil form used and other conditions. The performance will generally be adequate with liquid velocities below 85% of the input yarn velocity, provided the velocity is well in excess of the critical velocity for streamline flow. Yarn has been handled satisfactorily at input velocities varying from 250 to 5650 feet per minute. In general, the higher the yarn velocity the greater the ease of operation and the lower can be the ratio of liquid velocity to yarn velocity before unsatisfactory operating conditions are encountered. All yarns experimented with performed satisfactorily at input velocities of 250 feet per minute or higher when good tube material and coil formations, 25 providing a non-uniform shape of passage, were employed.

Table II gives some specific data developed in the washing of viscose rayon yarn, some twisted and some untwisted, in coils of different lengths with widely varying conditions of water pressure and flow. The yarn was taken up on a winder spindle driven by a constant torque motor so that fluctuations in delivery indicating non-uniform treatment could be observed. In all of these tests the yarn action was good and, except in the first test, the wind-up was steady. In Example 4 the coil was a simple helix. In all the others the coil shape was the oval having inwardly bent sides described in connection with Fig. 5. Under the heading "Injector dimensions," D refers to the inside diameter of tube 26 (Fig. 2), D' is the outside diameter of tube 25, d is the inside diameter of tube 25, and L is the distance tube 25 protrudes into tube 26.

TABLE II

Ex. No.	Tube, I. D., Inch	Tube Length, Feet	Coil Diameter, Inches	Water Pressure, Lbs./Sq. In.	Water Velocity, Inches/Minute	Yarn Speed, Inches/Minute	Injector Dimensions, Inches				Yarn, Denier	Yarn Twist, Turns/Inch
							D	D'	d	L

laxed processing, the input yarn velocity should be in excess of the liquid velocity in the tube. In this case the condition which prevails in the coiled tube is such that the linear velocity of any point of yarn in the tube is substantially the same as the water velocity at that point. The yarn, however, is in an undulated disposition so that the number of feet per minute of yarn passing a given section of the tube exceeds the linear velocity of any point on the yarn and also exceeds the water velocity through that same tube section. When tension is desired for processing purposes, the desired amount of tension is supplied at all points by having the liquid velocity in the tube greater than the input yarn velocity by a controlled amount. In either case the liquid velocity in the annular orifice of injector 20 must exceed the input yarn velocity.

The velocity of the fluid through the tube is determined by the dimensions of the injector parts, the pressure at which fluid is supplied to the injector and the diameter and length of the tube. By suitably selecting the

Example 9

In another trial 1100 denier viscose rayon yarn with 2.5 turns per inch of twist was washed acid free in two 50-foot coiled tubes at a yarn speed of 275 feet per minute and a mean water velocity through the tubes of approximately 219 feet per minute.

The apparatus of this invention can also be used for gaseous treatment of yarn and the like. Table III gives data obtained in removing water from nylon and viscose rayon yarns using preheated air or unheated air with the tubular coil submerged in a hot oil bath, or a combination of both methods of heating. In Example 10 the yarn was 1/2 twist, 210 denier nylon. In Example 11 the yarn was 1/2 twist, 150 denier nylon. In all other cases the yarn was 0 twist, 150 denier viscose rayon.

In each run the yarn sample was accurately weighed in the room dry state. It was then passed through a water bath and rewound. The increase in weight was measured,

and the yarn was then supplied to the tubular dryer at a controlled rate. The yarn leaving the dryer was again wound into a package and re-weighed to determine the amount of moisture removed. A $\frac{1}{4}$ inch inside diameter metal tube was employed in all tests, and the air flow was determined to be approximately one cubic foot per minute. The data show that 0 twist, 150 denier viscose yarn with 190% added water can have all of the water removed in a 10-foot length of coiled tubing when the yarn speed is 300 feet per minute and there is no pre-heating of the air.

TABLE III

Ex. No.	Weight of Water Divided by Weight of Dry Yarn	Temperature of Oil Bath Surrounding Tube (°F.)	Temperature of Input Air (°F.)	Temperature of Air at Tube End (°F.)	Tube Length, Feet	Percent Water Removal
10.....	.818	No bath.....	Not Meas.	180	20	101
11.....	.897	180.....	Not Heated.....	123	20	98

19.....	1.92	250.....	do.....	200	20	102

The coil shapes discussed are merely illustrative of workable shapes. As indicated by Example 4, a simple helical coil of tubing having a circular cross-section can be used satisfactorily with yarn bundles of normal size under certain conditions. This is especially true if the yarn is twisted, the tube has a suitably uneven surface, the injector is of optimum design, the fluid velocity is at substantially 85% of input yarn velocity, and the length of tube and number of turns are not excessive. This is also the case with large bundles of filaments, such as staple tow, which may have a total denier of from 55,000 to 230,000 denier. In such cases large tubing of from 1 to 3 inches may be used and may be operated only partly full of liquid to facilitate removal of vapor, such as carbon bisulfide. Tows of 167,000 and 226,800 denier were tested at an input tow speed of 100 yards per minute with 2 and $2\frac{1}{2}$ inch inside diameter rubber hoses coiled to an approximate $3\frac{1}{2}$ feet inside diameter helix. The performance was satisfactory with both cold and near boiling water. A hose length of 50 feet with a total drop in level of 3 feet was satisfactory with flow rates from 9 to 15 gallons per minute. The length of 167,000 denier tow in the $2\frac{1}{2}$ inch inside diameter tube was measured and found to be 90 feet with a flow rate of 9.1 gallons per minute.

The invention is especially suited to the washing, desulfuring, bleaching, relaxing and/or stretching of viscose rayon, although it may also be used in connection with solvent recovery, drying, heat treatment, impregnation or other modification of yarns, or the like. It has been found possible to uniformly wet process traveling yarns in a coiled tube of substantial tube length. Continuous operation with the yarn free of tension or under controlled tension is made possible. Automatic string-up of the yarn at the first and any subsequent coils of a series is provided, with substantially complete replacement of treating fluids between coils. The apparatus can be made at low cost, and the operating and maintenance costs are low. The equipment is fully enclosed so that air-conditioning of the room is not necessary.

As many apparently widely different embodiments of this invention may be made without departing from the spirit and scope thereof, it is to be understood that the invention is not limited to the specific illustrations given except as defined in the appended claims.

What is claimed is:

1. An apparatus for treating filamentous structures with fluid which comprises a reservoir chamber for treating fluid; a funnel-shaped opening connecting the lower

part of said chamber with a small exit tube of sufficient size to accommodate the filamentous structure to be treated, said tube extending a short distance inside of the end of a larger tube and forming therewith an annular orifice, the opposite end of said larger tube being connected to a long, coiled tube; an annular chamber surrounding said small tube and communicating with said annular orifice; means for supplying treating fluid under pressure to said annular chamber; means for supplying treating fluid to said reservoir chamber; and means for continuously introducing a filamentous structure to be

treated into said reservoir chamber to pass with treating fluid through said funnel-shaped opening, through said exit tube and through said coiled tube.

2. An apparatus for treating filamentous structures with fluid which comprises a reservoir chamber for treating fluid; a funnel-shaped opening connecting the lower part of said chamber with a small exit tube of sufficient size to accommodate the filamentous structure to be treated, said tube extending a short distance inside of the end of a larger tube and forming therewith an annular orifice, the opposite end of said larger tube being connected to a long, coiled tube; an annular chamber surrounding said small tube and communicating with said annular orifice; means for supplying treating fluid under pressure to said annular chamber; means for supplying treating fluid to said reservoir chamber; and means for continuously introducing a filamentous structure to be treated into said reservoir chamber to pass with treating fluid through said funnel-shaped opening, through said exit tube and through said coiled tube, comprising an inlet tube projecting into the upper part of said reservoir chamber, means for continuously introducing the filamentous structure through said inlet tube in a high velocity fluid stream, and a separator tube in approximate alignment with said inlet tube adapted to catch said fluid stream and conduct it away from said reservoir chamber, the end of said separator tube being covered with a screen set at an angle to deflect said filamentous structure out of said fluid stream toward the lower part of said reservoir chamber.

3. An apparatus for treating filamentous structures with fluid which comprises a reservoir chamber for treating fluid, a small exit tube of sufficient size to accommodate the filamentous structure to be treated communicating with the lower part of said chamber, said tube extending a short distance inside the end of a larger tube and forming therewith an annular orifice, a long coiled tube forming an extension of said larger tube, means for supplying treating fluid under pressure to said annular orifice, means for supplying treating fluid to said reservoir chamber, and means for introducing a filamentous structure to be treated into said reservoir chamber to pass with treating fluid through said exit tube and through said coiled tube.

4. Apparatus as defined in claim 3 in which said coiled tube is in the form of a coil having a plurality of reverse curvatures so that a taut filamentous structure will contact the tube wall for only a short distance

at any place before being drawn out of contact with the surface.

5. Apparatus as defined in claim 4 in which said coil has the shape of a compound helix.

6. Apparatus as defined in claim 3 in which said coiled tube has a flattened cross-section and has been twisted lengthwise prior to coiling so that the resulting coil formation is a compound helix.

7. Apparatus as defined in claim 3 in which said coiled tube has an irregular inner surface so that reduced resistance to passage of the filamentous structure results from fluid flowing between the structure and the tube surface to prevent binding.
